UNITED STATES PATENT OFFICE.

ADRIEN KORNFELD, OF GENEVA, SWITZERLAND, ASSIGNEE TO THE FIRM J.
LAMBERCIER & CO., OF GENEVA, SWITZERLAND.

INCANDESCENT LAMP FOR LIQUID FUELS.

Application filed August 4, 1921. Serial No. 429,889.

To all whom it may concern:

Be it known that I, ADRIEN KORNFELD, a citizen of Poland, residing at Geneva, Switzerland, 2 Place Montbrillant, have invented 5 certain new and useful Improvements in Incandescent Lamps for Liquid Fuels (for which I have filed an application in Germany, April 23d, 1920, No. 50,345), of which the following is a specification.

10 The invention relates to an incandescent lamp adapted to burn without a wick, without an auxiliary flame and without pressure, and intended for use with liquid fuel, such as petroleum, benzine, benzol, carbureted al- 15 coh, denatured alcohol, and the like, in which the flame is normally slightly above the fuel receptacle and, if required, may also be placed in other positions.

The use of a wick for the purpose of carrying the fuel from the receptacle, notwithstanding its advantages, is eliminated in the present invention, by reason of its fouling by the impurities of the liquid fuel, particularly if denatured alcohol is involved, 25 and its coking in the vaporizer. This fouling and coking has an increasingly injurious action on the capillary action of the wick, whereby the power to raise the liquid and hence also the tension of the combustible va- 30 pors to the Bunsen ejector are reduced, so that an incandescent lamp utilizing a wick must be taken apart very often and the wick be changed with the attendant difficulties.

35 The use of an auxiliary flame is objectionable in that it must be present continually inside the lamp, below the fuel container, and it also renders the construction and adjustment of the lamp complicated and un- 40 necessarily expensive.

With the use of pressure in such lamps for raising the liquid fuel from the container to the Bunsen burner, even a slight height, in order to obtain the best possible 45 mixture and the most brilliant and economical flame, the disadvantage here is that use must be made of a hermetically closed fuel container, from which the most minute quantity of fuel must not be permitted to flow. In addition, with the use of pressure, the danger is very great that the liquid fuel 50 will discharge at the mouth of the ejector and spread around the entire burner, and often take fire.

The new incandescent lamp is constructed 55 on the following two basic ideas:

1st. The principle of the simultaneous double descent, whereby on the one hand the liquid fuel, by reason of its own weight, flows through a tube from the container, and 60 on the other hand, the recovered heat of the flame is passed downwardly. The two finally unite in order to convert the liquid fuel into combustible vapors in a vaporizer. The latter is positioned on the base plate of 65 the lamp and at a relatively great distance below the container, so that the air openings of the Bunsen ejector have a very large and accessible space between the container and the vaporizer; 70

2nd. The principle of the double recovery and the double downward passage of the heat of the flame to the vaporizer, on the one hand through the metallic conductor of 75 the Bunsen burner and on the other through the direct passage of the heat through combustible vapors, which are first passed above the vaporizer to the flame and then, after being superheated by the flame, are passed downwardly; 80

The invention will be described herein- 85 after in detail in connection with the accompanying drawings, in which:—

Figure 1 is a vertical sectional view of a lamp embodying the invention.

Fig. 2 is a similar view of the upper portion of the lamp of a slightly modified construction.

Figs. 3, 4 and 5 are similar views of other modifications.

Fig. 6 is a side view of a lamp embodying another modification.

In Fig. 1, the annular container 1 receives the liquid fuel and is arranged at suitable height. Through a thin tube 2 the fuel is 95 passed from above downwardly, that is, from the container to the base of the lamp. A tube 3, of relatively large diameter, constructed of thin, poor heat conducting metal, for example German silver, forms the lower 100 part of the vaporizer and of the burner. The whole is arranged in the vertical axis of the lamp and attached in a depression in the center of the base plate of the lamp. The lower end of the tube 3 is closed by a 105 screw-threaded metal plug, by which free access to the interior of the vaporizer is obtained, so that the latter may be easily and

directly cleaned. Inside tube 3 there may be provided a metallic filter or the like extending to the upper part of the vaporizer, which always permits the free passage of liquid fuel, but catches all vapor residues. Pipe 2 empties at the lower end of pipe 3 into the latter, the liquid flowing from below therein through the vaporizer and upwardly.

10 The arrows on the drawing indicate the course of the liquid from the container to the vaporizer.

The liquid level in the heat insulating tube 3 is designated by 4, 4, and the vaporizer as well as the entire burner is supported by pipe 3. The incandescent sleeve 5 is supported on a nickel support 6, and 7 is the blue flame space of the Bunsen burner. Arranged in the center of the flame space 7 is a heat recovery metal rod 8, which extends for a certain distance below the flame space. The grate or network of the lamp is indicated by 9, while the upper part forming the head of the Bunsen burner is designated 10. Radially extending metal strips 11 are soldered on the one hand to the lower part of the central rod 8 and on the other to the inner walls of the burner head 10. 12 and 13 designate respectively 25 the Bunsen mixing pipe and the air supply pipe, 14 being the ejector nozzle screwed in the upper part of the vaporizer. The latter is divided by a tight partition 15 into two compartments, 16 being the ejector chamber and 17 the vaporizing chamber or compartment. At the top of compartment 17, below the partition 15, is soldered a tube 18, through which passes the combustible vapors from below upwardly in contact 30 with the superheating flame from space 7. The tube connected with the tube 18 and serving for passing the combustible vapors again back to the vaporizer is designated 19, and the end of this tube is soldered to 40 the ejector compartment 16 above the partition 15. The different arrows show the direction of flow of the combustible vapors and their exit through the ejector nozzle 14 vertically from below upwardly in the 45 axis of the burner. The rod 8 and the vaporizing chambers 16 and 17 form a unit with relatively thick walls of good heat conducting metal, for example, red or semi-red copper. While the lamp is in operation 50 the heat taken from the flame in space 7 is passed downwardly toward the vaporizer over two paths, namely, first through the metallic burner, and secondly through the pipe 19 for the superheating vapors. Some- 55 what below the level 4, where the vaporizer is soldered to the tube 3, the heat rays meet. The combustible liquid flowing downwardly through the tube 2 rises in the tube 3 and arrives somewhat above the level 4, 60 where it is subject to a temperature suf-

ficiently high and having sufficient heat to convert it into vapor. 20 is the pan for the burning alcohol, 21 the gallery or ridge or flange of the burner, and 22 the glass cylinder.

When the lamp is not in use the level of the liquid in the fuel container and in the ascensional tube 18 is equal. It is evident therefrom that under no circumstances, when the lamp is not in use, can the liquid 70 pass to the fall pipe 19 and flow out of the ejector 14. The tube or pipe 18 extends above the level of the fuel container. During the time in which the lamp is not used, the tension of the combustible vapors 75 at the mouth of the ejector amounts to 0. At the moment of use, however, by reason of the heating of the burner by the alcohol burning in the pan 20, the liquid level in the tube 18 begins to fall through the 80 formation of combustible vapors. At the same time the tension at the mouth of the ejector 14 gradually rises. At the moment 85 at which the liquid arrives at the height of the level 4 this tension is mathematically 90 equal to the height between this level and the liquid level in the container increased by the specific density of the liquid used. It is preferable to arrange the vaporizer as far below the container as possible. The 95 depth of the level in the container then exerts less influence on the tension of the vapors in the ejector.

There is simultaneously effected, through the relatively great length of the mixing 100 pipe, an intimate admixture of air with the vapors, at a lower tension of these vapors, even in such cases where the vapors contain a great deal of carbon, as for example, with benzine and petroleum. In order to 105 be able to arrange the vaporizer as low as possible, it is of advantage in this system, when the lamp begins to burn, that the double heat recovery be effected, first 110 through the metallic tube and second through the transmission of the vapors.

Any suitable means (not shown) may be utilized for extinguishing the lamp.

Fig. 2 shows a modification of the metallic connection between the central rod 8 and the burner head 10. The radially extending strips 11 are not used in this case, but the grate 9 is soldered on to the rod 8 and the burner head 10. In this arrangement use must be made for the grate of good heat conducting metal. The same figure shows a modification of the upper part of the ascending and descending tube 18 and 19. Instead of this upper part surrounding the flame space 7 in the form of an arc, as in 115 Fig. 1, the two tubes are placed so as to form a straight rod, which lies vertically against the flame space 7, the heat from which heats the tubes 18 and 19 by radiation. In this modification the flange 21 120

supporting the glass cylinder and the incandescent sleeve is an integral unit, and for this purpose there is provided in the lower portion of the flange, an opening 23, 5 with or without a tube, for the reception of the pipes 19 and 18.

According to the embodiment of Fig. 3, the two tubes 18 and 19 are also placed against each other, but here they are not adjacent to but in the flame space 7. It is evident that under these conditions the central rod 8 can not be positioned in the manner before described, but that it must be formed of a pipe 8, concentrically surrounding the tubes 18 and 19 and which is attached either to the grate made of heat conducting material or to radially extending strips 11.

Fig. 4 shows an arrangement in which the central tube for recovering the heat is omitted, and the heat recovery takes place through the metallic walls of the tubes 18 and 19, the upper parts of which extend into the flame space 7. For this purpose the walls of this tube are made of thick, good heat conducting metal. The tubes are soldered either to the heat conducting grate 9 or to the radial strips 11, which latter bring them in direct metallic contact with the burner head 10.

It is to be noted that with certain fuels, for example, benzine, benzol and carburetted alcohol, which generate a high temperature, although vaporizing at relatively low temperature, the upper part of the tube 18 and 19 need be brought only to the level 24 below the flame space, as shown in Fig. 4, although of course, above the container 1. The two tubes are thus in direct accord with this level, wherein they traverse the burner or surround it in the form of a soldered chamber for heating the vapors (Fig. 5).

The lamp illustrated on Fig. 6 is made according to the above described principles, but differs therefrom in that the container 25 for the liquid fuel is not arranged below the flame but at the same height or even above it. It is evident that in the latter case the tubes 18 and 19 must be arranged inside the cylinder 22 slightly above the likewise elevated container 25. The container 25, which for convenience may have an annular, or other form, is placed in the shade 26.

What I claim and desire to secure by Letters-Patent is:

1. A standing incandescent lamp for gravity fed liquid fuel comprising a Bunsen burner tube having an ejector and an air supply opening, a mantle arranged at the upper end of said tube, a vaporizing chamber arranged at the lower end of said tube and adapted to be heated by a heat conducted by said tube, a fuel reservoir ar-

ranged above the vaporizing chamber, a pipe for conveying fuel by gravity from the container to said chamber, a fuel conveying tube having one of its ends communicating with said vaporizing chamber and its other end connected to the first mentioned tube for supplying fuel to said ejector, said second mentioned tube extending upwardly from the vaporizing chamber to a point sufficiently close to the wall of said mantle to be heated by the flame and then extending downwardly to its place of connection with the first mentioned tube, the fuel passing through said second mentioned tube being also adapted to heat said vaporizing chamber, and heat conducting means associated with said burner tube to permit heat from the flame space of the mantle to heat the burner tube.

2. An incandescent lamp as claimed in claim 1 in which the last mentioned means includes a thick-walled conductor formed of good conducting metal.

3. An incandescent lamp as claimed in claim 1 in which the vaporizing chamber is connected to an insulating member in the form of a thin-walled tube of poor heat conducting material.

4. An incandescent lamp as claimed in claim 1 in which the vaporizing chamber is connected to an insulating member in the form of a thin-walled tube of poor heat conducting material, and a removable plug closing one end of said thin-walled tube.

5. A standing incandescent lamp including a standard, a fuel reservoir supported by said standard, an insulated tube arranged at the lower end of said standard, a pipe for conveying fuel by gravity from the reservoir to the lower portion of said tube, a burner tube having its lower end connected to the upper end of said insulated tube, said burner tube being provided with an internal partition having an internal chamber, an ejector nozzle arranged in the burner tube and receiving fuel from said chamber, the lower portion of said burner tube forming a vaporizing chamber, a fuel conveying tube having its lower end connected to the vaporizing chamber and extending upwardly above the upper end of said burner tube and from this point extending downwardly and having its other end connected to said internal chamber, an air port provided in said burner tube for admitting air to the latter, a heat conducting member arranged at the upper end of said burner tube and adapted to convey heat to the latter and a mantle arranged at the upper end of the burner tube and surrounding said heat conducting member.

In testimony whereof I affix my signature.

ADRIEN KORNFELD.
